UNITED STATES PATENT OFFICE.

PHILIP J. ROBINSON, OF LEOMINSTER, MASSACHUSETTS.

CABINET FOR DISK RECORDS.

1,082,361.

Specification of Letters Patent. Patented Dec. 23, 1913.

Application filed August 12, 1912. Serial No. 714,713.

To all whom it may concern:

Be it known that I, PHILIP J. ROBINSON, a citizen of the United States, residing at Leominster, in the county of Worcester and State of Massachusetts, have invented certain new and useful Improvements in Cabinets for Disk Records; and I do declare the following to be a full, clear, and exact description of the invention, such as will enable others skilled in the art to which it appertains to make and use the same.

This invention relates to furniture, and more especially to cabinets; and the object of the same is to produce an improved rotary cabinet holding phonographic disk records on edge and in narrow compartments where they will be protected from dust and handling but from which any desired record may be ejected instantly.

The invention consists principally in the means for latching or locking each record in its compartment, and in special provision which is made for adapting the cabinet to records of different sizes.

Details will appear in the following specification and claims, and are shown in the drawings, wherein—

Figure 1 is a front elevation of this improved cabinet showing some of its upright partitions, a few of the disk records in place, and one of the retainers tilted downward. Fig. 2 is an enlarged cross section through a portion of said cabinet, showing one of the compartments therein and illustrating in dotted lines how the retainer holds the disk in place whether at the rear or at the front of the compartment. Fig. 3 is a bottom plan view and Fig. 4 a side elevation of the male member of the pivot hereinafter described; and Fig. 5 is a top plan view, and Fig. 6 a side elevation of the female member of this pivot. Fig. 7 is a side elevation, partly broken away, of the filler hereinafter referred to; and Fig. 8 is a cross section thereof. Fig. 9 is a bottom plan view of a simple form of the cabinet, showing the pivot as attached to its base. Fig. 10 is a vertical section through another form of pivot employed on extra large cabinets.

The cabinet comprises a base or pedestal, and a body or casing, both of the desired size and ornamentation forming no part of the present invention excepting that ordi-

narily this device is kept in the parlor or on exhibition in the store, and I would prefer that it be tasteful and that it be of proper material to withstand the use to which it is to be put. As to its size, if it is not the intention that a large number of disk records are to be stored therein the body or casing may be small and will doubtless be mounted fixedly upon the base or pedestal by means which need not be illustrated; but where many disks are to be stored in the cabinet it will necessarily be large, and in that case I would mount it rotatably upon the base or pedestal in a manner to be described below. If the cabinet be small the compartments in which the disks are stored will open only at its front, if it be larger the compartments may be disposed back to back so as to open on two sides of the casing and the latter will be suitably supported upon the base, and if the cabinet be quite large its compartments may open on all four sides and in which event the pivot and latch will be modified accordingly as will yet be explained. But whatever the size of the cabinet, the construction of each individual compartment and the means for locking the disk therein and releasing it when desired will be the same, and therefore a description of one will suffice for all.

Referring now more particularly to Figs. 1 and 2, each compartment comprises a floor 1 which will doubtless be a board forming the bottom of the casing, and a track which in the present instance is shown as a groove 2 cut in the upper face of said floor and depressed into a rest 3 near the front edge 90 thereof so that the groove inclines toward the open front of the cabinet or the entire floor inclines as illustrated; an upright fixed back 4 which will be the rear wall of a single cabinet or the intermediate wall of a double-faced cabinet; and a top which is a specially constructed member and will be described in detail below. This top is located such distance above the floor as to accommodate twelve inch disk records, but when it is desired to store smaller records in the cabinet, as for instance those measuring ten inches in diameter, a filler best seen in Fig. 7 is employed. This consists of a narrow board 5 having a tongue 6 along its lower edge shaped to fit into the groove 2

and rest 3 in the track, and thereby held from slipping off. The board is cut in its upper edge with a groove 7 and depression or rest 8 similar to those in the upper face 5 of the floor 1 excepting that the groove 7 will be longer than the groove 2 and the rest 8 will be struck on a circle of smaller radius as will be clearly understood. If this filler be two inches high, when put into place in 10 any compartment the latter will accommodate a ten inch record and the radius of the curve on which the rest 8 is struck will be such as to correspond with a record of that size; and it is obvious that a smaller 15 or larger filler can be inserted in any compartment so as to cause the same to accommodate records of various sizes. It is quite within the spirit of my invention that the filler shall be a board extending completely 20 across the interior of the casing and resting upon the floor 1, with grooves 7 and 8 cut transversely across its upper face and in proper position to overlie those in the fixed floor 1; and if a filler of this character be 25 employed, the entire casing may be at once altered so that it will accommodate nothing but smaller records and all of them of one size. However, as a filler of this kind would in effect be nothing but a series of fillers as 30 shown in Figs. 7 and 8 secured side to side, I have considered it hardly necessary to illustrate the amplified idea. The top of each compartment, below the true top of the casing, is occupied by a retainer best seen in 35 Figs. 1 and 2. This member is a block 10 having in its lower edge a longitudinal groove 12 extending from near the rear end to a point 11 a little forward of the center of the length of the block where the groove 40 makes an angle with the deeper portion or cut-out 13 which is continued in line with the groove to and through the front end of the block. The whole is mounted on a pivot 14, which may be a cross rod extending 45 throughout the casing and on which all of the blocks may be pivoted side by side. Rising from the upper edge of each block above its pivot is an eye 15 with which is loosely linked the inner end of a rod 16 that passes 50 through the front wall 17 of the casing and carries a knob 18 on its forward extremity, a spring 19 being interposed between said wall and knob so that the latter is pressed normally forward and the block normally 55 canted downward at its forward end as seen in Fig. 2. When the retainer stands in this position the disk record D will be held housed within the casing, its lower edge resting in the groove 2, its rear edge standing 60 nearly or quite in contact with the back 4, and its upper edge standing within the groove 12 to the rear of the angle 11. When now it is desired to withdraw a record, the record is selected by reading a suitable number or character inscribed on the head of 65

the knob 18, and the operator presses that knob; the result is that he compresses the spring 19, pushes the rod 16 to the rear, and rocks the block 10 on its pivot 14 so that the angle 11 rises and the disk D is freed and 70 permitted to roll down the groove 2 until it comes to rest within the depressed portion 3 thereof as seen, and its front edge projects beyond the cabinet so that it may be grasped by hand. Thus it will be seen that a disk 75 is delivered from the casing through its own gravity which causes it to roll down the inclined track as soon as the retainer is elevated, rather than by being ejected forcibly by means of mechanism so commonly employed in devices of this character. Without further description or illustration, it 80 will be clear that a small-sized disk mounted within any compartment in the casing would follow the same rule and roll down the track 85 on the upper edge of the filler as soon as it is released by the retainer. When the disk has come to rest within the depressed portion 3, the operator is free to release his pressure upon the knob 18 so that the retainer drops and its cut-out 13 rests gently 90 on the upper edge of the disk to hold the latter in position ready to be grasped by the operator and drawn out of place at his leisure. After the disk is used, it is obviously restored to its proper compartment by 95 pushing it into place, this action simply raising the retainer around its pivot 14 until the highest point on the disk has passed the angle 11, after which the spring 19 causes 100 said angle to descend and the disk is held by the groove 12 at the rear portion of the retainer like all others which are stored within this cabinet. The width of each compartment will be only a trifle greater than the 105 thickness of the disk record, and it is quite within the spirit of my invention to omit the side walls which separate the compartments, as indicated at 20, and to store the records within the casing side by side and 110 almost but not quite in contact with each other, although in that case I would provide a door to close the normally open front of the casing and exclude dust. When the partitions are employed and the size of the 115 entire cabinet must be kept down, they may be of metal or perhaps of cardboard but in any event they will be as thin as possible, as they may be because there is no strain upon them. I would, however, make them removable in some way in order that occasionally the 120 operator can withdraw the partition and sweep or dust out the interior of the casing, because in time a certain amount of dust is bound to accumulate therein.

A feature of my invention consists in the fact that the retainers are mounted at the upper portion of the interior of the casing, rather than at the rear or at the bottom, and therefore they will not accumulate dust 125

which might interfere with their successful operation. This fact also permits the partitions to be removed and the interior of the casing cleaned with ease, and even washed if necessary, because the lower side of the blocks 10 will hardly need anything more than dusting.

Another feature of my invention might be called secondary because it is not employed unless the cabinet is sufficiently large to necessitate it. This is the special means for mounting the casing upon the base or pedestal 21, which latter may rest upon a table or have feet 22 if it stands upon the floor. In Fig. 1 I have shown the casing as provided with casters 23 movable over a plate 24 secured upon the upper face of the base 21, so that the entire casing can be rolled or turned thereon at will and the operator may thus gain access to any side of the casing. In Figs. 3 to 6 I have shown a special form of pivot consisting of a male member secured beneath the casing and a female member let into the top of the base, so that the casing is rotatably mounted upon the base and is held frictionally in any position to which it is turned. The male member comprises a plate 30 having a central depending pin 31 surrounded by a plurality of sockets 32 of which two are shown in the present instance, and the plate is screwed to the bottom of the casing as at 33. The female member consists of a plate 40 having a central depending boss 41 provided with a cavity 42 into which the pin 31 enters and within which it may rotate freely; and the plate 40 is let into the face plate or top of the base or pedestal and secured in place by screws 43. Mounted within an upright hole 44 through the plate 40 and boss 41 is a spring 45 which sustains a ball 46 at its upper end in a position to be borne upward with yielding force into any of the sockets 32, and this spring is pressed upward by a screw plug 47 in the lower end of the hole 41. When the casing is mounted on the base by means of this pivot, it can be rotated easily, and the spring-pressed ball 46 will be pressed upward into the sockets 32 as the male member rotates with the casing. If the latter be sufficiently large to have four of its sides devoted to compartments for the disks D, the plate 30 will have four sockets 32 set quartering to each other, although it will be clearly understood that there could be a greater or lesser number of sockets and that they should correspond with the faces of the cabinet devoted to compartments.

The construction illustrated in Fig. 10 is designed for an extra large sized cabinet whose casing when filled with records would be so heavy that it would hardly be safe to mount it on a single pivot without some means for reinforcing the latter and preventing the tilting or tipping of the casing.

Therefore I provide casters 50 carried by the bottom of the casing 1 and traveling on a ring-shaped track 51 mounted on the upper face of the base 21, this track being of considerable size. In addition to the casters 70 I also provide a central pivot consisting of a male member 53 having sockets 54 and a central depending pin 55; and a female member 56 having a cavity 57 for the pin, much like the construction above described. In this case I would pass a screw 58 through a washer 59 and up into the lower end of the pin 55, the washer being of sufficient size to underlie the boss in which the cavity 57 is bored, this detail being useful for absolutely preventing the tipping over of the casing off of the base. With so large a cabinet I would substitute for the spring-pressed ball and sockets above described, a treadle 60 whose free end is normally supported by a spring 61 and whose inner end is mounted pivotally as at 62 in an ear 63 depending from the female member through the top of the base 21, and connected with this treadle is a pin 64 sliding vertically and a tubular boss 65 depending from the female member and with its tip adapted to be pressed upward by the spring 61 into any of the sockets 54 as the latter are moved over it. With this construction, the operator by depressing the treadle also depresses the pin 64, and then the entire case can be rotated around its central pivot, the pin 55 turning in the cavity 57 of the female member and the casters 50 traveling around on the track 51; and when the proper face of the casing has been brought to the front, the operator will release pressure on the treadle 60 and the spring 61 will cause its pin 64 to rise so that it springs into the socket 54 in the male member which next comes over it. Thereafter the desired disk D is ejected by pressing the proper knob 18 as at first described above.

Thus it will be seen that I have produced a cabinet for disk records which is adapted for those of various sizes up to the maximum, if we assume that said maximum is twelve inches in diameter; which is adapted to permit the instant ejection of any record desired or its replacement after it has been used; which may be built in sizes according to the uses to which it is to be put; and which if made large enough will be mounted on a special pivot with a special spring-actuated latch to hold any face of the casing forward with the records in that side of the casing ready for instant removal or replacement.

It will not be necessary for the purposes 125 of this invention to amplify the construction of details further than has been done, nor to show and describe the doors with which the open front or sides of the cabinet may be provided, although such doors are not abso- 130

lutely necessary. I reserve the right to make changes in details such as come within the spirit of this invention.

What is claimed as new is:—

5. 1. A cabinet for disk records comprising a casing having a series of open front compartments whereof each has a floor inclined downward and forward and provided near its front edge with a rest so disposed that 10 when the record rests therein its edge will project out of said open front; combined with a retainer pivoted in the top of each compartment and having a shoulder in its lower edge, that portion of the retainer in 15 rear of the shoulder adapted to engage a record when resting on the floor in rear of said rest and the portion forward of the shoulder to engage a record when resting in the rest, and means for turning the retainer 20 on its pivot.
2. In a cabinet for phonographic disk records, the combination with a casing whereof each record compartment has a floor inclined downwardly and forwardly and a depression between the front end of said incline and the front of the casing; of a retainer pivotally mounted in the top of the casing and having its lower edge grooved on two lines with a shoulder between said lines 25 occurring substantially above the point between the inclined floor and its depression, for the purpose set forth, and means for actuating said retainer.
3. A cabinet for phonographic disk records having a series of upright compartments each consisting of a floor inclined toward the open front of the cabinet and having a rest near its front edge, a retainer at the top of the compartment consisting of a 30 block pivoted near its rear end and having in its lower edge a groove with a shoulder in its length, and a rod loosely connected with said block and extending through the front of the cabinet and there having a knob.
45. 4. A cabinet for phonographic disk records having a series of upright compartments each provided at its bottom with a track inclined downwardly and forwardly and having near its front end a rest, an upper back at the rear of the compartment, a 50 right back at the rear of the compartment, a retainer at the top of the compartment consisting of a block having in its lower edge a

groove, a cut-out at its front end, and a shoulder between said groove and cut-out, and means for disengaging the block from the record.

5. In a cabinet for disk records, the combination with a casing having an open front, and a floor therein having a groove in its upper face inclined downward and forward 60 and provided near its front edge with a rest so disposed that when the record rests therein its edge will project out of said open front; of a retainer pivoted in the top of the casing and having its lower edge 65 grooved at its rear end and cut out at its front end, said cut-out coacting with said rest for the purpose set forth, and manually controlled means for turning the retainer on its pivot.

76

6. In a cabinet for phonographic disk records, the combination with a casing having an open front and a floor inclined downward and forward toward said front; a retainer for each record consisting of a block 75 pivoted near its rear end in said casing and having in its lower edge a longitudinal groove with a cut-out at its front end and a shoulder between the groove and cut-out, a spring for normally depressing said front 80 end, and manually operable means for overcoming the tension of the spring and swinging the retainer on its pivot, for the purpose set forth.

85

7. In a cabinet for disk records, the combination with a casing having an open front, and a floor therein having a groove in its upper face inclined downward and forward and provided near its front edge with a rest so disposed that when the record rests therein its edge will project out of said open front; of a retainer pivoted in the top of the casing and having a depending shoulder between its front and rear edges, a spring tending to swing said front downward, and manually-controlled means for raising the retainer at will.

90

In testimony whereof I have hereunto set my hand in presence of two subscribing witnesses.
